UNITED STATES PATENT OFFICE.

WILLIAM A. CASWELL, OF CHICAGO, ILLINOIS, ASSIGNOR, BY MESNE ASSIGNMENTS,
TO NATIONAL DUMP CAR COMPANY, A CORPORATION OF MAINE.

RAILWAY-CAR.

1,093,828.

Specification of Letters Patent. Patented Apr. 21, 1914.

Application filed July 11, 1903, Serial No. 165,096. Renewed February 26, 1914. Serial No. 821,287.

To all whom it may concern:

Be it known that I, WILLIAM A. CASWELL, a citizen of the United States, residing in Chicago, in the county of Cook and State of Illinois, have invented a new and useful Improvement in Railway-Cars, of which the following is a specification.

This invention relates to dump cars and is an improvement upon the dump car shown 10 in my application No. 135,949, filed December 20th, 1902. The improvements mentioned, however, are not restricted to their application to the particular car shown and described in that application.

15 The nature of the present improvement is fully set forth in the description given below, and will be understood from such description when considered in connection with the accompanying drawings, in which:—

20 Figure 1 is a side elevation of my improved car. Fig. 2 is a plan view thereof. Fig. 3 is a partial central vertical section. Fig. 4 is a partial horizontal section. Fig. 5 is an end elevation. Fig. 6 is a partial 25 transverse section of the bolster. Fig. 7 is a similar section of one of the needle beams. Fig. 8 is a partial vertical longitudinal section through the end of the car. Fig. 9 is a similar section taken through one of the 30 needle beams. Fig. 10 is a similar section through the central header. Fig. 11 is a similar section on the line 11—11 of Fig. 6. Fig. 12 is a similar section through the bolster. Fig. 13 is a side elevation of one of the 35 pins on the door supporting shaft. Fig. 14 is an enlarged partial plan, partly broken away. Fig. 15 is a vertical section of the door and one of its hinges. Fig. 16 is an enlarged elevation of a portion of the end 40 of the car, showing the details of the mechanism for operating the door supporting shaft. Fig. 17 is a still more enlarged section of said mechanism, taken longitudinally of the shaft. Fig. 18 is a detailed plan of said 45 mechanism, and Fig. 19 is a section of the line 19—19 of Fig. 18.

In said drawing, 20 represents the longitudinal sides of the car, 21 the ends, 22 the stationary portion of the floor, 23 the dump 50 doors forming the balance of the floor, 25 the end sill, and 26 the center sills. There are four of the latter, and the doors are hinged to the outer ones, and open at their outer sides, so that the discharge is outward from the car. The hinges of the doors

are illustrated in detail at Figs 14 and 15. The doors have at their under side, transverse straps 27, having eyes which embrace the pintles 28, carried by blocks 29, supported upon the outer center sills 26, and 30 having depending ears 30 setting behind the center sills. Each door is provided along its hinged edge with a flat plate 31 continuous from end to end of the door and projecting inward therefrom slightly beyond the pintles 28. The car is also provided with plates 32 arranged along the door openings and over the hinges, and extending outwardly over the plates 31 as plainly shown at Fig. 15. These plates 32 are secured to the center beam by bolts 33, and that portion of them which laps over the plate 31 is curved upward, as also shown in said figure, so that when the door swings, room will be afforded under the plates to allow the plates 31 to 70 keep their edges in contact with the curved portions which are concentric with the pintles.

In the closed positions, the outer edges of plate 32 are in contact with the top of plates 80 31, so that the plates are adapted to co-act in excluding dust, dirt and grain or other fine substances with which the car may be loaded, from the hinges, and should any of the fine material gain access to the space between the plates, it will be removed by the plates 31 when the doors are opened, as the plates 31 will then force the material outward as the movement proceeds. The plates 31 are secured to the doors by bolts 34. This 85 construction of the hinge covering, not only excludes the material being carried from the hinges while in transit, but also when the doors are opened, as the two plates form a close junction in all positions of the door. 95

The doors are supported by rolling supports consisting of shafts 40 having upon them rollers 41 supporting the doors and pinions 42, 43 and 44 supporting the shafts and serving as a means of moving them 100 bodily to and from the outer one of the center sills in opening and closing the doors. There are two of these shafts on each side of the car, each shaft serving to support a portion of the doors on the same side of 105 the car therewith. The rollers 41 are arranged under the plates or straps 27 by preference, so that they may not cut into the wood of the door. The pinions 43 at the outer ends of the shafts engage racks 110

45 in the end sills, while the pinions 42 engage racks 46 in the needle beams and intermediate headers and the pinions 44, which are placed upon the abutting ends of 5 two shafts at the center of the car, mesh with racks 46 similar to those shown in Figs. 7 and 9. The pinions 43 and 44 are only half the width of the pinions 42, but all the pinions are provided upon at least 10 one side, with rims 47 of the same diameter as the toothed portions and adapted to ride and support the shaft upon the upper and substantially horizontal ends 48 of the racks when in position for closing the doors. The 15 racks are all adapted to permit the coal dust or dirt and fine material, which may lodge upon them when the doors are opened, to be forced off them by the pinions, as more particularly set forth below. The shafts are 20 all movable bodily toward the center sills when the doors are to be opened and they are arranged longitudinally of the car and parallel to the sills, as will be understood from what had already been written. In 25 these movements the shafts traverse slots 49 in the end sills, bolsters, needle beams and headers, the racks mentioned being arranged in and forming the bottom of the slots. The bodily movements of the shafts 30 are obtained by rotating them by means of levers 50, pivoted upon them and having reversible dogs 51 engaging ratchets 52 fast on the shafts. The levers are adapted to impart movement in either direction desired, depending upon whether the door is 35 to be opened or closed. The levers encircle thimbles 53, which interiorly conform to the shafts but are round exteriorly, thus allowing the levers to be turned on the shafts 40 in either direction. I also provide means for locking the shafts when they are holding the doors closed against turning or moving bodily off the horizontal ends of the racks under the influence of the jarring of 45 the car when in motion. For this purpose I provide on the ends of the car, keepers 54, having U shaped slots 55, into which the ends of the levers may be inserted as shown particularly at Figs. 18 and 19. These 50 keepers are located in such position as to engage the levers when the latter are depressed into a nearly horizontal position, and as the keepers are located inside the shafts when they are holding the doors 55 closed, it will be seen that any tendency by the shafts to move inward under the jarring received from the car, will create an end thrust of said levers against the ends of the slots 55, which, of course, will act to 60 prevent any shifting of the shaft in this manner. The keepers are also adapted to receive sealing devices 56, such sealing devices passing through openings 57 in the sides of the slots 55, so as to confine the 65 ends of the levers in the keepers and pre-

vent them from rising out of the slots. The keepers thus serve to confine the levers against movement in all directions in which there is any tendency for them to move.

The spaces between the teeth of the racks 70 45 and 46 are deepened or cut away as more particularly shown at 58 in Fig. 12, so that if fine material gets in between any pair of teeth, the pinions, when they pass said teeth, will tend to force the material down and out 75 of the space, the space being either bottomless except at the center, or having a bottom sloping downward in both directions from the center as at 58. The end sill has a rack corresponding in width to the pinion 43, and if preferred, instead of cutting 80 out the metal wholly under the ends of the teeth, openings 59 may be formed through the bottom of the rack adapted to give exit to the fine material lodging on the rack 85 and the same is true of the end portions 48 of the racks. This ability to clear the racks automatically of the deposited material is of great importance, as by it the attendants are relieved of the labor of clearing 90 off the racks preparatory to closing the doors, the racks if not self clearing, being so constructed as to permit the easy escape of the material when the teeth of the pinions enter them. 95

One of the end sills is shown at Fig. 5. It is made in one solid piece extending from side to side of the car and provided with the slots 49, top rib 60, bottom rib 61 and central vertical rib 62, and opening 63 for 100 the draft rigging and opening 64 at each end, and with openings 65 in such number as may be necessary to avoid the presence of unnecessary metal in the web of the sill. It is also provided with openings for the 105 ends of the truss rods 66 and the central end stakes 67 are bolted to it as plainly shown. At the corners of the superstructure, are angle posts 68 and 69, the latter being inside and the former outside, of the 110 side and end planking, and one web of the outside post is carried down and riveted to the end sill as seen at 69^a.

The bolster is best illustrated at Fig. 6. It consists of a rectangular casting 70 at 115 each side of the center sill, in which is formed the slot 49 and the rack as will be understood. The web is cut out as shown at 71 to remove unnecessary metal. At the inner ends, the casting is bolted to wood 120 beams 72, the bolts passing through the outside center sill. These beams not only stiffen the sills to which they are attached but they afford a means for the attachment of the flooring 22. Between the outer center sill 125 and its companion sill is a metal frame 73 fitting both sills and bolted to both of them. A second wood beam 72 is also bolted, preferably to the companion sill. Fig. 6 shows only one half of the bolster, the other half 130

being constructed in the same manner and a metal frame 74 being placed between the two inner sills. At its outer end, the frame 70 is bolted to the longitudinal plank 100, 5 which is united to the side planking of the car by metal straps 101. The lower edge of this longitudinal plank is protected by an angle bar 102, and the bolts attaching this plank to the frame 70 are preferably passed through the strap and angle bar. The outer end of the frame 70 is adapted to admit the foot of a metal stake 103, made of T iron and bolted to the casting 75 as shown at 104. Under each of the inner center sills, I place 15 a reinforcing channel iron 78 extending from the end sill to a point between the bolster and the adjacent header. The reinforcement is cut out at the top as seen at 79 in Fig. 3 so that it can be inserted from below and bolted to the frame 80 of the casting 75. This frame 80 together with the flange 76 of the casting 75 forms the union between the two halves of the bolster and gives room for the draft rigging, it being 20 understood that the casting 75 comprises in an integral structure the web with its lower flange and upper flange 76, and the frame 80 extending across the central part of the car. While Fig. 6 shows only half the width of 25 the car the casting 75 extends integrally from side to side of the car, the two ends of the bolster being of the same form. The plate 81 under this frame 80 is intended to support the draft rigging. The frame 70 has an opening for the rod 82 which acts as 30 a stop to limit the opening of the doors and the frame 73 is adapted to give room to the truss rod 66.

One of the needle beams is shown at Fig. 40 7. Like the bolster, it has a rectangular casting at each side of the center sills, which is shown at 90, and which is cut out at 91 to reduce the metal, and contains the slot 49 for the door shaft. Below the casting 90 45 and below the center sills are two channel beams 92, placed back to back and bolted together and also to the center sills. A depending bracket 93, having an arm 94 extends up between the two beams 92 and 50 flanged at 95. This bracket forms one of the low points for the truss rod 66 and is duplicated for the other truss rod. The stake 103 opposite the needle beam extends down and is fastened to the channel beams 55 92 as plainly shown, the casting 90 being adapted to fit the stake. The intermediate headers are shown at Fig. 10 in detail and are like the needle beam in all respects except that the channel bars 92, are of reduced 60 strength and the castings do not have the projecting ends 96, and the brackets 93 are not present.

The truss rods 66 are attached to the end 65 sills as shown at 66 in Fig. 5 and after passing the bolster are deflected down under the

brackets 93. In addition to these truss rods which are of the ordinary construction, I provide side truss rods 120 fully shown at Figs. 1, 2, 5, 6 and 14. They start from the end sills at 121, thence extend up to the top 70 of the side planking over the bolster, thence down to the level of the floor at the needle beam and from the first needle beam to the second needle beam, thence upward to the top of the side planking in the plane of the 75 other bolster, and down to the attachment to the other end sill. The castings 90 of the needle beams have projections 96 at their outer ends each with a perforation at 97 adapted to receive the truss 120. By means 80 of this exterior truss rod, which of course is duplicated at the other side of the car, I greatly aid in sustaining the load and reducing the amount of camber, and it is peculiarly useful in cars where the sides 20 form 85 girders for supporting the longitudinal center of the car. In the car shown, the girder sides and the outside truss rods unite in giving the center such perfect support as to render the usual side sills unnecessary. The 90 car is further provided with a pair of truss rods 130 extending from bolster to bolster and secured to them near the line of the outer center sills. From their attachment to the bolsters, they are deflected horizontally 95 outward and pass through both pair of beams 92 at 132, thence back to the bolster at the farther end of the car. These truss rods are desirably though not necessarily located below the sills and their purpose is to 100 enable the car to better withstand the strains to which it is subjected when it sways side-wise, or in other words they serve to stiffen the car laterally. Around the inside of the 105 car and near the floor is a line of inclined faced beading 140 adapted to deflect the load into the door opening when the door is opened.

Although I have described the plates 31 as flat, it will be understood that they need 110 not be flat throughout, and in fact the rear edge 35 of those shown is bent upward so as to come flush with the top surfaces of the doors as seen at Figs. 14 and 15. The horizontal ends 48 of the racks 45 and 46 are 115 provided with side flanges in the planes of the rims 47 upon the pinions and adapted to form tables or supports for said rims as will be understood from the description heretofore given. When the doors are 120 closed, the shafts are held against turning in one direction by the slots 49 and in the other direction by the keepers resisting the end thrust of the operating levers. And in order 125 that there may be no tendency to lift the levers out of the keepers, such as would be occasioned by any turning of the shaft, I disengage the levers at such times from the ratchets 52, so that their sole function in conjunction with the keepers while the doors 130

are closed, is to exert an end thrust against the keepers and thus prevent any departure of the shafts from their proper position. The plates 32 not only serve to keep dirt, dust, etc., from getting into the hinge joints of the door, but where the hinges are separable by a vertical movement of the doors which is the preferable construction, serve also to retain the doors in the hinges, and 10 are secured after the doors have been positioned.

The car is provided at each cross frame member with a cross tie rod 135 extending from side to side of the car, and the space 15 between the center sills at the cross frames, other than the bolsters are filled by plates 133, and secured in place by cross bolts 134. (See Fig. 7.)

I claim:—

20 1. In a dump car, the combination with a hinged door of a flat plate carried by the door and covering the hinges, and a stationary curved plate overlapping the plate upon the door, and effecting a tight joint 25 therewith in all positions of the door.

2. In a dump car, the combination with a hinged door of a stationary member of the car frame, a plate supported thereon and having its projecting edge curved upwardly 30 as shown, and a coacting plate carried by the door and projecting over the hinge, and adapted to substantially maintain contact with the under side of the curved portion of the plate on the frame member, in all positions of the door.

3. The dump car having in combination with a hinged floor door, a plate on the door covering its hinge, and a stationary plate secured to and forming part of a level floor of 40 the car and overlapping said door plate, and curved so that the door plate may substantially maintain contact therewith in all positions of the door.

4. The dump car having hinged doors in 45 its floor, forming when closed part of a level floor, longitudinal plates secured to the doors along their hinged sides, and the stationary plates secured to and forming part of said floor along the door openings and lapping 50 over said door plates, and curved concentrically with axis of the hinges.

5. The dump car having hinged doors in its floor forming when closed part of a level floor, longitudinal plates secured to the doors 55 along their hinged sides and extending over the hinges, and plates secured to the stationary part of said level floor and themselves forming a part of the same floor, and also extending over the hinges and over the 60 door plates, said last mentioned plates being curved so their under surfaces will be in contact with the door plates in all positions of the latter.

6. The combination with the dump car 65 and its plate overhanging the door hinges

of the center sill, the blocks secured to the sill and carrying the stationary part of the hinges, and the floor plate also overhanging the hinges above the door plates and curved concentrically of the axis of the hinges, whereby a dirt excluding joint is formed between said plates effective in all positions of the door.

7. The combination with the hinged dump door of a rolling support therefor, embodying a shaft mounted on pinions, and stationary racks with which the pinions mesh and located in the cross members of the car frame, said racks being cut away between their teeth to give escape to any material 80 falling upon them.

8. The combination with a hinged dump door, of a rolling support therefor embodying a bodily movable shaft, pinions supporting said shaft, and stationary racks traversed by said pinions, said racks being cut away between the teeth so the pinions are enabled to force out any lodging material.

9. The combination with a hinged dump door, of a rolling support therefor embodying a bodily movable shaft, pinions supporting said shaft, and stationary racks traversed by said pinions, said racks being cut away between the teeth and below their plane so that the pinions are enabled to force 95 out any lodging material.

10. The dump door having a rolling support, which moves in and out in opening and closing the door, and pinions and racks beneath the door for imparting such movement to the support, such racks having their interspaces cut away to give exit to the deposited material.

11. The combination with the dump door of a railway car, and a rolling support for 105 such door movable transversely of the door to open and close the door, of ways traversed by said rolling support and beneath the door, such ways being constructed to allow the easy escape of such material as 110 may fall upon them from the car when the support moves over them.

12. The combination with the dump doors, of the shaft supporting the same, rimmed pinions upon the shaft, and ways traversed 115 by the pinions, such ways having horizontal portions upon which the pinions rest while the doors are being held closed.

13. The combination with the dump doors, of the shaft supporting the same, rimmed pinions upon the shaft, and ways traversed by the pinions, such ways having horizontal untoothed portions upon which the rims of the pinions may rest while the doors are being held closed.

14. The combination with the doors and their supporting shaft and pinions, of ways traversed by the pinions and having untoothed portions upon which the rims of the pinions rest while holding the doors closed,

- of means for locking the shaft against moving from said untoothed portions of the ways.
15. The combination with the doors and their supporting shaft and pinions, of ways traversed by the pinions and having untoothed portions upon which the rims of the pinions rest while the doors are held closed, a lever for operating the shaft, and a keeper for such lever adapted to resist its end thrust.
16. The combination with the doors opening outwardly, and a shaft and pinions supporting the doors and movable inwardly to open them, of ways traversed by the pinions and having plain portions on which the rims of the pinions rest while the doors are held closed, a lever for operating the shaft, and a keeper for locking said lever located on the side of the shaft toward which it moves in opening the doors.
17. The combination with the doors of a dump car, of a rolling and bodily movable shaft for supporting the doors, and ways for sustaining the shaft, of a lever for turning the shaft having a dog and ratchet connection thereto adapted to be used in either direction.
18. The combination with the continuous exterior side truss rods, of needle beams having projecting ends with openings through which the rods pass.
19. The combination with the side planking serving as girders, of reinforcing side trusses engaging the cross framing under the central portion of the car body, and supported near their ends upon the side of the car.
20. The car whose side planking serves as girders, and is combined with side truss rods engaging the central cross framing of the car and supported near their ends above the plane of the car sills.
21. A railway car having a series of hinged dumping doors in its bottom, a shaft mounted in the underframe of the car for supporting and operating said dumping doors, said shaft having a bodily movement of translation, and means applied directly to the end of the shaft for operating the shaft.
22. A railway car having a bottom comprising a series of dumping doors, a shaft mounted in the underframe of the car for supporting and operating said dumping doors, said shaft having a bodily movement of translation, a lever mounted upon the end of the shaft, and means connecting the lever and the shaft, whereby the shaft may be operated by the lever.
23. A railway car having a series of hinged dumping doors, a bodily movable shaft parallel to the hinge axis of said doors, means for supporting said shaft beneath and adjacent the free edge of said doors when closed, means mounted on and movable with said shaft for rotating the same, and means for closing said door by rotation of the shaft.
24. The bolster, the upper portion whereof consists of a series of castings, and the lower portion of a single piece casting, open at the center to admit the draft rigging.
25. The combination with the castings 70 and 75 of the stakes 103 fitted in the ends of both castings, and bolted to them.
26. The combination in a needle beam of castings 91 extending from the center sills to the sides of the car, and continuous beams 80 placed under the castings.
27. The combination in a needle beam of castings 91 extending from the center sills to the side of the car and two continuous channel beams extending from end to end 85 of the needle beam.
28. The car having a cross frame member consisting of castings 91 filling the space between the center sill and the car sides, and wrought metal beams continuous from 90 side to side of the car and supporting said castings.
29. In a dump car, a rack having rack teeth upon its upper side, and inclined surface portions intermediate such rack teeth 95 for preventing the accumulation of material between the teeth.
30. A railway car having a series of hinged dumping doors in its bottom, a movable shaft mounted in the underframe of 100 the car and having a movement of translation for supporting and operating said dumping doors, a lever loosely mounted on said shaft, and means for preventing relative rotation of said lever on said shaft in 105 one direction while permitting relative rotation of said lever on said shaft in the opposite direction.
31. In a dump car, a door supporting shaft, adapted to be reciprocated by rotation thereof, a handle by which to rotate the shaft, and a stop for the outer end of the handle the parts being arranged to make the handle act as a strut from the stop to resist movement of the shaft away from the position of closure for the door.
32. In a dump car, a door supporting shaft, adapted to be reciprocated by rotation thereof, a handle by which to rotate the shaft, supporting means for the shaft in its 120 outermost position, and a stop to hold the handle so that it will act as a strut to keep the shaft on said support.
33. In a car, dump doors, a bodily movable and rotatable shaft, means for imparting bodily movement to said shaft when rotated, and means movable with said shaft for rotating the same.
34. In a dump car, a dump door, a supporting track, a bodily movable shaft co- 130

- acting with said track and door to operate the same, and means mounted upon said shaft and movable therewith for imparting movement to said shaft.
- 5 35. In a dump car, a dump door, a supporting track, a bodily movable shaft co-acting with said track and door to operate the same, means mounted on and movable with said shaft for imparting rotation thereto, and means to give said shaft a bodily movement of translation when rotated.
- 10 36. In a dump car, a dump door, a supporting track, a bodily movable shaft co-acting with said track and door to operate the same, a lever rotatably mounted on said shaft, a pawl on said lever, a ratchet and spur gear secured to said shaft, and rack teeth upon said support.
- 15 37. A railway car having a series of dumping doors in its bottom, a door support adjacent the free edges of said doors, a movable shaft adapted to lie between said doors and support and having a movement of translation to transmit the downward thrust of said doors directly to said support, and means mounted on said shaft and movable therewith for displacing said shaft from said support to permit said doors to open.
- 20 38. A railway car having a longitudinal series of dumping doors in its bottom, a shaft mounted in the frame of the car parallel to the hinge axis of the doors and having a movement of translation to open and close and to occupy a position beneath the doors at the outer edges thereof to support the doors and transmit the load therefrom to the frame of the car, and means mounted directly on the end of the shaft for displacing the shaft from supporting position.
- 25 39. A car having a series of doors in its floor hinged adjacent the center sill, a displaceable shaft mounted in the underframe of the car for operating and for supporting the doors in closed position adjacent the swinging edges thereof, an operating device loosely mounted on the end of the shaft and traveling therewith as the shaft is displaced from supporting position, and a clutch non-rotatively connecting said operating device to said shaft when rotated in one direction but permitting independent rotation of said device in the opposite direction.

WILLIAM A. CASWELL.
